UNITED STATES PATENT OFFICE

ALBERT S. LA FOLLETTE, OF KENOVA, WEST VIRGINIA

CLOTH-MEASURING DEVICE

Application filed July 27, 1928. Serial No. 295,824.

The object of this invention is to provide convenient means for showing the amount of cloth remaining on a bolt, by employing a tape constituting a measuring strip adapted to be coiled in a particular type of casing which in turn is mounted in a novel manner on the end of the core board, and when a specified number of yards of cloth are sold, the same length of tape will be unwound and detached as a part of the sale record, the remainder of the tape showing in yards the quantity left on the bolt.

A further object is to provide a plurality of detachable elements constituting a housing for the tape, one element of the housing being adapted to be rotated with reference to the other in the first stage of the unwinding operation, said elements of the housing carrying respectively a mounting device and a label or tag holding device.

With the foregoing and other objects in view, the invention consists in the novel construction and arrangement of elements described, illustrated and claimed, it being understood that modifications may be made within the scope of the claims without departing from the spirit of the invention.

In the drawings:—

Figure 1 is a perspective view showing a bolt of fabric with the measuring device applied to one end of the core board.

Figure 2 is a section thru the housing or casing of the attachment.

Figure 3 is also a section thru said housing in a plane passing thru the axial member of the rotatable device forming one element of the housing.

Figure 4 shows the elements of Figure 3 detached.

Figure 5 is an elevation showing one side or end portion of the housing or casing, and means for securing a tag thereto.

A bolt of cloth or other fabric is shown conventionally and is designated 10 and a core board is designated 11, this board receiving a resilient forked mounting device 12, forming a part of the attachment and secured thereto as by means of a rivet 13, providing pivotal movement at that point and

avoiding too direct contact with the shelf or table.

The attachment per se includes a main casing member 14 having a flange at the edge portion thereof, as shown in Figures 3 and 4, and the casing further includes a plate member 15 on which the mounting device 12 is secured. The element 14, of slightly less diameter than plate 15 is rotatable with reference to the latter, this movement being effected by hand, as when rewinding surplus tape after detaching, for measuring purposes, the length to be cut off when making a sale. Rotation also occurs in the first stage of the unwinding operation.

The plate 15 carries a central sleeve or hub member 16 having an enlargement of annular form at 17, the device just referred to being retained by flared portion 17. The element 16 is of tubular form as indicated and the complementary element 19, carried by casing member 14 will also be of tubular form, preferably, and provided with a split portion 19'. Element 19 is rotatable, is secured by flared portion 20, and has an enlargement or flange portion 21 for cooperation with enlarged portion 17 on the member 16, when the tubular portions are positioned concentrically.

The casing elements thus constructed are adapted for cooperation in the manner indicated in Figure 3 of the drawing, providing a suitable housing for coiled tape 22, to be wound on the element 16.

In order to mount a tag, label, or the like 24, on the outer side of the casing, I provide deflected tongues or ears 25, as shown in Figures 4 and 5, and these elements are adapted to engage the edge portion of the tag in opposite relation, said tag providing for any data to be entered thereon, pertaining to the goods carried by the core board. A resilient retaining device for the tape is mounted at 30 along side of the slot 31, and retains the end portion of the tape in convenient position, as shown in Figure 2.

Having described the invention what is claimed is:—

In a device of the class described, a casing comprising a plate, resilient forked means

for connecting the plate with a core board,
a centrally located boss carried by the plate
and including an annular enlargement, a
5 flanged plate including a split tubular mem-
ber for engagement with said boss and in-
cluding an annular enlarged portion having
annular interlocking engagement with the
enlargement first named, the flanged portion
of the second named plate being slotted.

10 In testimony whereof I affix my signature.
ALBERT S. LA FOLLETTE.
